(57) **CLAIM**

The ornamental design for a connection buckle, as shown and described.

DESCRIPTION

FIG. 1 is a first perspective view of a connection buckle showing the new design;

FIG. 2 is a second perspective view of the connection buckle showing the new design;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a first explosive view thereof; and,

FIG. 10 is second explosive view thereof.

The broken lines in the drawings show portions of the connection buckle which form no part of the claimed design.
